7 Claims. (Cl. 99—171)

2

The present invention pertains to a package and a liner therefor and more particularly to a liner for a container adapted to impart increased rigidity to the container and to enable improved packing of articles therein.

The subject invention overcomes several problems of the prior art to which brief preliminary reference is made. Until recent years, cantaloupes have been packed in wooden crates. However, for various reasons, such as the weight and expense of wooden crates, the modern trend in fruit packaging is to the use of cardboard or fiberboard boxes. In addition, cantaloupes and other perishable products are frequently bruised by being jammed into wooden crates.

Because the normal weight of a box of cantaloupe is approximately sixty pounds, and because the side walls of packed boxes are often subjected to considerable moisture if allowed to remain over extended periods in refrigeration cars, the insulation properties, the wet strength and rigidity of the boxes must be substantial to withstand the stresses involved.

For years packed boxes of fruits and vegetables have been stacked on their bottom and top walls in railway cars for transport. Recently, it has been decided to stack the boxes on end in the cars primarily since it enables loading a greater number of boxes in the cars. This presents new problems which previously known fiberboard containers are unable to solve. The fruit naturally settles during shipment, causing the side, top and bottom walls of such containers to bulge outwardly. This is especially true with relatively heavy fruit such as cantaloupes. The pack becomes loose or slack so that travel of the car causes jostling of the fruit and increases the opportunities for bruising.

A cardboard box that has achieved popularity for fruit packaging includes three releasably interfitted sections requiring a minimum number of staples to form a completed box. The outer and intermediate sections are of the same shape although the former is slightly larger than the latter, slidably to receive the same therein; these sections having top and bottom walls, respectively, an open bottom and an open top, respectively, and rectangularly arranged side and end walls. The inside section has an open top, rectangularly arranged side and end walls adapted to be slidably fitted within the intermediate section, and end and side bottom wall flaps foldable between an open position and a bottom wall forming position. The intermediate section is transported and stored, prior to use in flattened condition. In use, stacks of the same are placed adjacent to the packing line of a packing house. Packers pick off the sections, fold them into rectangular box forming shape and fold in the bottom wall portions; the latter are not sealed and are rested on a table, or the like, to prevent them from opening; and the sections are filled with fruit. In order to lift a loaded intermediate section, it is obviously necessary to hold the bottom wall flaps closed. The reason the bottom wall flaps are unsealed is to reduce to a minimum the number of operations the packer must perform. Although this speeds up production at one stage, it causes delays and inconvenience in handling the intermediate section once it is loaded. Ordinarily, the inner section is inserted into the intermediate section to hold the bottom wall flaps closed.

Another problem relates more specifically to cantaloupes. Although cantaloupes are graded according to certain established size classifications, as a practical mat-

ter, the actual size and shape of cantaloupes within a particular size classification usually vary slightly. Because of these size variations, the pack may be too loose so as to rattle or cause bruising, or the upper surface of the upper layer may be uneven. It is to be observed that the appearance of a box of cantaloupes is of considerable commercial importance.

Accordingly, it is an object of the present invention to provide a liner for a container which is adapted to strengthen and make more rigid fiberboard containers and the like.

Another object is to enable improved packing of articles in boxes made of cardboard, paperboard, fiberboard, and the like.

Another object is to enable cardboard boxes to be stacked on end without the contents thereof causing bulging of the side walls of the box.

Another object is to maintain a compact, tight pack of articles in a container and to minimize loosening of the pack.

Another object is to minimize jostling and consequent bruising of fruit in a box during shipment and other handling of the box.

Another object is to provide a pack of cantaloupes of slightly different sizes and shapes which has an upper layer providing a substantially flat upper surface.

Another object is to enable the lifting and carrying of a section of a box having unsealed bottom wall portions which is loaded with articles.

Another object is to reinforce the longitudinal rigidity of fiberboard boxes and the like.

Another object is to minimize outward bulging of the side walls of a box.

Another object is to provide a liner for a box having partitions between layers of fruit in the box which partitions accommodate themselves to variations in fruit sizes and shapes.

Another object is to provide a resilient liner for a container which yields under weight of articles placed thereon and when forced thereagainst by closure of the cover for the container but which raises articles upwardly when the cover of the container is open to provide an improved display and to minimize fruit bruising.

Another object is to provide a liner for a container which is conducive to automatic packing of the container.

Another object is to provide a liner for a container which contacts the stem ends of fruit in layers on opposite sides of the liner and which incorporates a mold and decay inhibitor to prevent the incipience of mold and decay normally having its origin at said stem ends.

Other objects are to provide a liner of the nature described which is economical to construct and use, adaptable to a variety of articles, although particularly suited to produce, dependable in operation, and which is highly effective for accomplishing its intended purposes.

These, together with other objects, will become more fully apparent upon reference to the following description and accompanying drawings.

In the drawings:

FIG. 1 is an exploded perspective view of a container and a liner constructed in accordance with the principles of the present invention.

FIG. 2 is a somewhat enlarged longitudinal section taken through the inner and intermediate sections of the container with the liner of the present invention fitted therein and showing layers of cantaloupes packed in the container.

FIG. 3 is a somewhat enlarged transverse section through an assembled container of the type shown in FIG. 1, and incorporating the liner as well as upper and lower layers of cantaloupes.

With reference to FIG. 1, a container 10 with which

the subject invention is especially adapted for use is shown prior to assembly of its various parts. This container includes an intermediate section 11 having a substantially rectangular bottom wall 12 providing a plurality of elongated, longitudinally extended slots 13, and opposite upwardly extended side and end walls 14 and 15 integral with the bottom wall and interconnected along their adjacent corners in substantially rectangular relation. The end walls provide horizontal, elongated hand-receiving openings 16.

The container 10 also includes an inner section 20 which provides opposite side and end walls 21 and 22 integrally connected along their corner edges in substantially rectangular relation. The end walls 22 also provide hand-receiving openings 23. A bottom wall 24 includes a pair of end flaps 25 integrally foldably connected along the lower edges of the walls 22 and a pair of side flaps 26 integrally foldably connected to the lower edges of the side walls 21. The side and end flaps are movable between overlapping positions in substantially a common plane so as to form a bottom wall of the inner section and open positions outwardly and downwardly retracted from the bottom wall forming positions. It is to be noted that the flaps provide slots 27, and that the slots in the end flaps register with the endwardly located slots in the side flaps when the flaps are in said bottom wall forming positions. The inner section of the container is of such size that it can be releasably slidably fitted into the intermediate section 11 with the end and side walls of the respective sections in sliding engagement, with corresponding hand-receiving openings 16 and 23 in registration, and with corresponding ventilating slots 13 and 27 in registration.

Still further, the container 10 has an outer top section 35 including a rectangular top wall 36 and downwardly extended end and side walls 37 and 38 connected in rectangular relationship. The outer section is adapted to be releasably slidably fitted over the intermediate section with the respective side and end walls 14, 15, 37 and 38 in engagement. The end walls of the outer section have hand-receiving openings 39 respectively in registration with the hand-receiving openings 16 and 23 when the outer section is in the described fitted relation.

The container 10 as described above is of conventional construction and has been explained in some detail in order to enable a better appreciation of the operation and use of the subject invention. It is to be understood, however, that the present invention is not limited to the use of this type of container.

A liner 45 constructed in accordance with the principles of the present invention is also illustrated in FIG. 1. The liner includes a substantially rectangular bottom panel 46 of substantially the same size as the bottom wall 24 of the inner container section 20. The bottom panel is adapted to be fitted in overlaying relation with the bottom wall of the inner section and includes elongated slots 47 in registration with the slots 27 in said bottom wall. The bottom panel has opposite side edges 48 extended along and engaging the side walls 21 of the inner section, and end edges 49 engaging the end walls 22.

The liner 45 provides a pair of side panels 55 of substantially rectangular form having lower edges integrally foldably connected to the side edges 48 of the bottom panel 46 and longitudinally extended top edges 56. The side panels also have opposite end edges 57 engaging the end walls 22 of the inner section 20 when the liner is positioned therein. The side panels are provided with elongated, longitudinally extended side wall portions 55' against the side walls 21 of the inner section 20 of the container 10 and fold lines 58 substantially parallel to and intermediate the lower and top edges 48 and 56 so as to enable folding the side panels inwardly toward each other to provide a pair of partitions 59 in substantially parallel relation to the bottom panel 46 and in substan-

tially coplanar relationship with each other. The partitions are edgewardly spaced from each other in their inwardly folded positions so as to define an elongated vent passage 60 extending the length of the container.

5 Although not shown, the outer surfaces of the side panels can be provided with corrugations adapted for non-slidably frictional engagement with the adjacent side walls 21 of the inner container section 20 when forced thereagainst under predetermined pressure.

10

Operation

The operation of the described embodiment of the subject invention is believed to be readily apparent and is briefly summarized at this point.

15 As explained, the liner 45 is especially suited for use with the type of container described and indicated by the numeral 10. In actual use of this container in a packing house, the inner sections 20 and the liners 45 are stacked in flattened folded condition adjacent to the packing line. It is to be observed that the inner section 20 may be folded into a flat condition by opening or retracting the bottom wall flaps 25 and 26 and then by folding the side and end walls 21 and 22 along their corner folds into parallelogram form and finally into face-to-face engagement.

20 In order to pack the container 10 with cantaloupes, indicated by the numeral 65, the inner section 20 is opened into rectangular form and the end and side flaps 25 and 26 are folded into their bottom wall forming partitions and placed on a packing table, not shown, or other supporting surface. The liner 45 is then fitted into the inner section with the bottom panel 46 overlaying the bottom wall 24, and with the side panels 55 extending upwardly in engagement with the side walls 21 of the inner section. 25 A first or bottom layer 66 of cantaloupes 65 is then placed either manually or mechanically on the bottom panel of the liner. Thereafter, the partitions 59 are folded along the lines 58 into overlaying relation with the bottom layer. Next, an upper layer 67 of cantaloupes is placed in the inner section 20 of the container 10 on the partitions 59. It is to be noted that the partitions form a relatively flat substantially continuous (except for the vent passage 60) surface, similar to the bottom panel 46, on which to place the top or second layer. Without the partitions, the second layer of cantaloupes would have to be placed on the relatively uneven surface provided by the lower layer of cantaloupes. It is to be noted that the subject liner is especially adapted for use with the automatic cantaloupe packing machine disclosed in the co-pending United States patent application S.N. 666,314, filed June 18, 1957. The partitions shield the lower layer of cantaloupes and minimize bruises thereof when the upper layer of cantaloupes is deposited in the container.

30 Partitions 59 also serve to equalize the total height of the layers 66 and 67 of cantaloupes 65 to provide a substantially even upper surface. Inasmuch as there are certain slight size and shape differences even within the same graded size of cantaloupes, without the partitions 59, two relatively smaller cantaloupes might be placed one on the other to cause the described unevenness. The partitions rest on the largest size cantaloupes and provide a more nearly horizontal surface upon which to place the upper layer of cantaloupes.

35 Furthermore, the partitions 59 take advantage of the described unevenness in the lower layer 66 of cantaloupes. The partitions are sufficiently flexible to yield slightly under the weight of the cantaloupes in the upper layer. Thus, as illustrated in FIG. 2, the cantaloupes in the upper layer immediately above the spaces between cantaloupes in the lower layer depress the partition slightly to form barriers 70 between the cantaloupes to maintain them in place in the layer. In like manner, this depression of the partitions creates pockets 71 for the cantaloupes in the upper layer. This provides a tighter,

more compact load within the box, avoids the described loose or slack pack, and minimizes possible and resultant bruising of the fruit. Further, it will be seen that the inwardly folded flaps or partitions 59 are securely held between the cantaloupes which in turn imparts substantially greater strength and reinforcing characteristics to the liner and box than otherwise would be obtained. It is also to be noted that the well-known rough, netted surface character of cantaloupes is utilized to advantage in gripping the partitions and clamping the same between the upper and lower layers.

When the inner section 20 is filled, it can be picked up by fitting the hands through the openings 23 and simply lifting the section. The side panels 55, frictionally engage the side walls 21 to prevent downward slideable movement of the liner 45 relative to the inner section. Thus, although the flaps 25 and 26 are not sealed, the cantaloupes 65 are dependably retained within the inner section. It is to be noted that the frictional contact between the side panels and the side walls is increased by the outward pressure of the cantaloupes. As above indicated, however, corrugations, not shown, may be incorporated on the outer surface of the side panels further to increase the frictional engagement, if desired.

The described clamping of the partitions 59 between the layers of cantaloupes 66 and 67 minimizes or obviates outward bulging of the side walls 21 of the inner section 20. In addition, the partitions impart longitudinal rigidity to the inner section because of their extension between and contact with the end walls 22. To complete the package, the inner section 20 is slidably fitted into the intermediate section 11, and the outer section 35 slidably fitted over the intermediate section. The top wall 36 bears against the upper layer 67 of cantaloupes 65 to hold them in their pockets 71 and otherwise cooperates with the bottom wall 12 and the partition 59 to provide the described characteristics. The container 10 can be positioned on one of its end walls 37 as well as on the bottom wall 12. When stacked on end, the partitions prevent the cantaloupes from settling downwardly and thereby prevent bulging of the bottom and top walls of the container. Of course, the partitions add longitudinal strength for end stacking purposes. The top wall further urges the upper layer of cantaloupes against the liner partitions which resiliently yield to form pockets of greater depth. When the outer section is removed, the partitions spring upwardly to raise the upper layer of cantaloupes. This minimizes bruising and provides a more attractive display.

From the foregoing it will be evident that a highly advantageous liner has been provided for use in a container. The liner enables more effective and efficient use of the described type of container having unsealed bottom wall flaps, provides partitions which strengthen the container, and enables improved packaging of fruit and other articles. The liner does not impair normal ventilation of the pack, is conducive to automatic mechanical packing, and may be impregnated with a mold inhibitor for further protection of fruit therein. In this latter regard, the liner offers another lamination, in effect, for the bottom wall of the container so as to add additional wet strength and insulating properties to the bottom wall.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described my invention, what I claim as new and desire to secure by Letters Patent is:

1. A packaged produce product comprising a sheet fiberboard container having a bottom and upstanding end walls and side walls defining an article receiving compartment; a reinforcing liner of sheet fiberboard material

which is substantially rigid in edgeward dimension although having limited resilience and flexibility in its thickness dimension, the liner providing a bottom fitted to the bottom of the container and side walls integral with the bottom extended upwardly along the side walls of the container; a lower layer of articles of produce tightly packed between the side walls of the liner and positioned on the bottom thereof, the liner having elongated partition portions integral with the side walls of the liner and inwardly extended in substantially parallel relation to the liner bottom each a distance approximately but less than one-half of the distance between the side walls, the partitions being in overlying engagement with the lower layer of articles; and an upper layer of articles of produce rested on the partition portions of the liner and tightly packed between the side walls of the container, said partition portions being substantially rigid in edgeward dimension and engaging the end walls and side walls of the container to impart rigidly thereto and said layers of articles of produce tightly clamping the partition portions therebetween.

2. A packaged product comprising a container having a bottom wall and opposed end and side walls interconnected in substantially rectangular relation and upstanding from the bottom wall, the side walls having upper and lower edges; a liner of sheet material which is substantially rigid although having limited resilience and flexibility in its thickness dimension, the liner being releasably slidably fitted in said container and including a bottom panel in congruent overlying engagement with the bottom wall, the liner having elongated side wall portions integrally foldably connected to the bottom panel and upwardly extended along the side walls of the container; a lower layer of such substantially spherically-shaped articles of produce positioned on the bottom panel in compressive engagement with the side wall portions, and urging the side wall portions of the liner tightly outwardly against the side walls of the container, the liner having elongated article overlaying and supporting partitions integrally foldably connected to the side wall portions along fold lines extended longitudinally of the side walls, said fold lines being held in spaced substantially parallel relation to and in substantially coplanar relation with said upper and lower edges of the container by the lower layer of articles, the partitions being extended transversely inwardly from the side walls and being freely pivotal about their respective fold lines upwardly and downwardly in the container above and below predetermined relaxed neutral positions, said partitions terminating in spaced inner edges opposite to and substantially coplanar with said fold lines, said inner edges being in spaced relation to the bottom panel to provide a ventilating passage therebetween and being freely movable upwardly and downwardly in the container away from and toward the bottom panel, the partitions being in overlying engagement with the lower layer of articles on the bottom panel but having portions which do not engage articles in the lower layer; and an upper layer of such substantially spherically-shaped articles of produce positioned on the partitions, the partitions being resiliently depressed by any article of the upper layer which is in engagement with said non-engaging partition portions thereby tightly clamping the partitions between said upper and lower layers, the partitions being substantially edgewardly rigid and having outer edges engaged against the side walls and end walls of the container substantially midway between the upper and lower edges thereof.

3. The package of claim 2 wherein the articles of produce in the upper and lower layers have outer roughened peripheries gripping the partitions therebetween and resisting movement of the partitions relative to each other longitudinally and transversely of the container.

4. A packaged produce product comprising a container of substantially rigid sheet material having interconnected end walls and side walls circumscribing an

article receiving compartment and providing a pair of bottom flaps foldably connected to the side walls for movement between substantially coplanar closed positions providing a bottom for the compartment and depending positions retracted from the compartment and opening the bottom thereof; a liner of substantially rigid sheet material slidably fitted into the container having a bottom panel positioned in closing relation to the bottom of the compartment, side panels foldably connected to the bottom panel and upwardly extending therefrom in frictional facing engagement with the side walls of the container, and partition panels foldably connected to the side panels and inwardly extended therefrom in substantially coplanar relation in parallel relation to the bottom panel; articles of produce packed within the liner thrusting the side panels thereof outwardly against the side walls of the container in frictional engagement therewith; and articles of produce packed in the container on the partition panels and clamping said partition panels against the articles packed in the liner, said partition panels being edgewards substantially rigid and having outer edges engaged against the side panels and end panels of the container to impart increased rigidity to the package, the produce being packed in the liner sufficiently tightly that frictional engagement of the side panels of the liner with the side walls of the container support the liner and articles in the container when the bottom flaps of the container are in depending position and said bottom flaps engaging the bottom panel of the liner in supporting relation thereto when in closed positions.

5. The packaged produce product of claim 4 including means telescopically fitted upwardly over the container releasably supporting the bottom flaps of the container in closed positions.

6. The packaged produce product of claim 4 including an intermediate member having integrally interconnected end walls and side walls slidably fitted upwardly over the container in slidable engagement with the end walls and side walls respectively thereof and including a bottom supporting the flaps of the container in closed positions; and an outer member slidably fitted downwardly over the intermediate member having integrally interconnected end walls and side walls slidably engaged with the end walls and side walls respectively of the intermediate member and a top in covering relation to the compartment of the container.

7. A packaged produce product comprising a container adapted to receive cantaloupes and having a flat bottom wall divided into a pair of freely separable flaps, a pair of opposed parallel side walls upstanding from the bottom wall, a pair of opposed end walls upstanding from the bottom wall and connected in substantially rectangular relation with the side walls, the bottom wall flaps

5 being foldable between bottom wall forming positions and positions downwardly retracted therefrom, and a top wall in substantially parallel relation to the bottom wall; a reinforcing liner for the container of sheet fiberboard material comprising a flat rectangular one-piece bottom panel having substantially the same length and width as the container and fitted in the container in overlying relation with the bottom wall thereof, and rectangular side panels having substantially the same length as the container and upwardly extended from the bottom panel in engagement with the side walls adjacent thereto; a layer of cantaloupes packed on the bottom panel of the liner tightly between the side panels thereof whereby the side panels are urged into frictional engagement with the side walls of the container, the side panels having substantially parallel fold lines extended longitudinally of the container in a substantially common plane parallel to the bottom panel and defining partition panels continuous with the side panels foldable along said fold lines between positions against the side walls of the container and positions substantially parallel to the bottom panel adapted to overlie and rest on the cantaloupes packed in the liner, said partitions each being of a width less than one-half of the width of the container and having spaced inner edges when folded into parallel relation to the bottom panel defining a ventilation opening therebetween; and a layer of cantaloupes packed in the container on the partitions, said partitions being sufficiently flexible in their thickness dimension somewhat 20 to conform to the shape of the cantaloupes on which said partitions are folded and the cantaloupes packed thereon so as to be clamped therebetween and having peripheral edge portions in engagement with the end walls and side walls of the container and being substantially edgewards rigid.
